ELECTRIC FENCE INSULATOR

Fredric C. Muntylyer, Sr., Palos Park, Ill., assignor to
Wire Machinery Inc., Chicago, Ill.

Filed Nov. 4, 1969, Ser. No. 19,943

Term of patent 14 years

Int. Cl. D13—99

U.S. Cl. D26—10

FIG. 6.FIG. 7.FIG. 8.

FIG. 1 is a top plan view of an electric fence insulator embodying my new design;

FIG. 2 is a side view of the insulator shown in FIG. 1;

FIG. 3 is an end view of the insulator looking along the line 3—3 in FIG. 1;

FIG. 4 is a transverse section looking along the line 4—4 in FIG. 1;

FIG. 5 is an angular section made generally transversely and looking along the line 5—5 in FIG. 1;

FIG. 6 is a transverse section looking along the line 6—6 in FIG. 1;

FIG. 7 is a front end view looking along the line 7—7 in FIG. 1; and

FIG. 8 is a fragmentary axial section looking along the line 8—8 in FIG. 2;

The broken lines are for illustrative purposes only.
I claim:

The ornamental design for an electric fence insulator, as shown and described.
